UNITED STATES PATENT OFFICE.

OLIVER MITCHELL, OF BROOKLINE, MASSACHUSETTS.

FOUNTAIN PEN.

Application filed September 27, 1921. Serial No. 503,584.

To all whom it may concern:

Be it known that I, OLIVER MITCHELL, a citizen of the United States, residing at Brookline, in the county of Norfolk and State of Massachusetts, have invented certain new and useful Improvements in Fountain Pens, of which the following is a specification.

My invention is an improvement in fountain pens and consists in the provision at the rear of the fountain or barrel of such a pen, of a means for withdrawing air from the barrel to a compartment at the upper end of the barrel, thus rarifying the air 15 in the barrel and causing an inflow of ink at the forward end of the barrel by the outer atmospheric pressure and later discharging the air from the upper compartment through a pipe leading from the upper compartment 20 to the pen end of the barrel. This operation is repeated as often as may be necessary to empty the barrel of air and fill the barrel with ink.

In the drawings:

Figure 1 is a longitudinal sectional elevation of a fountain pen embodying my improvement showing the interior parts as at the end of the air-expelling stroke;

Figure 2 is a cross-section on line 2—2 of Figure 1;

Figure 3 is a cross-section on line 3—3 of Figure 1;

Figure 4 is a partial sectional elevation of a modification; and

Figure 5 is a partial sectional elevation of the device of Figure 1, showing the interior parts as at the end of the outward stroke of the suction cup.

The mechanism of my improved pen is 40 of the simplest. The fountain 1 carries at one end the feed bar 2 having ink feeding fissures 3 and a pen point 4, as is usual. The ink feed bar has, in addition to the ink fissures 3 another passage 5, which at its 45 inner end is central of the bar and fountain, that is, corresponds with the longitudinal axis of the fountain and is connected with a pipe A extending axially of the fountain to near the top or rear end of the same.

Slidably fitting at the rear upper end of the fountain is a cup or chamber B, and within this chamber and frictionally engaging the same, is a disk C which is mounted upon the pipe A and has a slight capacity 55 for motion to and fro along that pipe, between stops a, a'. A packing c' at the edge

of disk C gives an air tight frictional engagement with the inner walls of cup B.

There is provided a suitable gland D which screws along the fountain to compress 60 a packing d, between the gland D and the upper, inner end of the fountain. Preferably in the closed end of the cup B, I provide a vent hole, normally closed by a screw plug, b, and at the open end of the cup, 65 I provide a gland b' to compress a packing b'' between the cup and the fountain.

Preferably on the interior surface of cup B, I provide a stop or stops, e, so placed as to engage the disk C when the cup has been 70 moved outwardly to the desired limit of its stroke.

The upper end of pipe A is open and is provided with a stop, a, between which stop and another stop a' the disk C may move 75 in a limited to and fro movement. When the disk C is at the lower end of its movement, resting against stop a', it covers and closes a hole or holes a^x communicating with the interior of pipe A (see Figure 1). When 80 disk C is at the upper end of its movement it uncovers and opens holes a^x thus forming a passage from the fountain on one side of disk C to the other, through the disk (see Figure 5). 85

The operation is as follows: The parts being assembled as shown in Figure 1, to fill the pen the pen end of the fountain is submerged in ink. The operator holding the fountain with one hand, grasps the 90 outer end of the cup B with the other and draws the cup outward. The first effect of this action is to shift the disk C upward, on pipe A, by the frictional engagement of disk C and cup B, thus opening the holes 95 a^x in pipe A and a passage from one side of disk C to the other through the disk. The stop, a, limits the upward movement of disk C and continued movement of cup B enlarges the space above disk C and induces a stream of air from below disk C to the interior of cup B, above disk C, through holes a^x and pipe A. The consequent rarification of air in fountain 1 disturbs the atmospheric balance below disk 100 C and causes ink to be forced into the fountain 1 and passage 5 and pipe A, by outside atmospheric pressure.

The cup B is now pushed inward. The first effect of this action is to shift the disk 110 C downward on pipe A, by the frictional engagement of disk C and cup B, until disk

C rests against stop a' , and covers and closes holes a^x , thus closing the passage for air from one side of disk C to the other side, which was opened upon the up stroke of cup B and simultaneously diminishing the space above disk C, forcing the air through pipe A and passage 5, to the outer air, and expelling all the ink that entered passage 5 or pipe A during the up stroke of cup B but in no wise affecting the ink drawn into the fountain proper, since the passage from the upper to the under side of disk C, above the ink in the fountain, was closed by the initial inward, air-compressing stroke of cup B and all air trapped in cup B is forced through the pipe A and passage 5. The ink in the fountain proper continually gains at each outward stroke of the cup B as the fountain ink is not subjected to any pressure on the inward stroke of cup B. All ink entering passage 5 or pipe A during an outward stroke of cup B is expelled on the next inward stroke of cup B, so that ink never gains in passage 5 and pipe A and when the cup B has been operated a sufficient number of times, the fountain will be filled and pipe A and passage 5, on the final instroke of cup B will be cleared of ink. The filling of the fountain with ink will be indicated to the operator by the gradual decrease of ejected air bubbles at the immersed end of the fountain. When the bubbles begin to diminish the operation of the cup B should immediately cease.

I preferably form within cup B a slightly conical member b^x which, when the cup is in its inner position, fits and plugs the open, inner end of pipe A.

I have shown and described above the preferred form and mode of operation of my device, in which the air is admitted on the up stroke of the cup, to the pipe and so passes through and above the disk. It is obvious, of course, that a separate aper-

ture might be formed in the disk, seating 45 against a shoulder and being closed thereby on the down stroke of the cup and lifted from the shoulder and opened on the up stroke of the cup. Such a modification is shown in Figure 4 in which the shoulder is 50 marked X, and the aperture in the disk C is marked c^x , the other parts being as in the other figures.

I claim:

1. In a fountain pen, the combination of 55 a fountain; a cup slidably mounted in the open rear end of the fountain; a pipe longitudinally mounted within the fountain, open at its front end to the air and at its rear end communicating with the interior 60 of the cup; a disk mounted for longitudinal movement upon the pipe at its rear end, within the cup and in frictional air tight engagement at its edges with the inner walls of the cup and having a passage there- 65 through, the disk moving to open the passage upon rearward movement of the cup and to close the passage upon forward movement of the cup.

2. In a fountain pen, the combination of 70 a fountain; a cup slidably mounted in the rear end of the fountain; a pipe longitudinally mounted within the fountain, open at its front end to the air and at its rear end communicating with the interior of the cup and with the fountain; a disk mounted for longitudinal movement upon the pipe at its rear end within the cup and in frictional air tight engagement at its edges with the inner walls of the cup, the disk moving to 75 open the passage from the fountain to the interior of the pipe upon rearward movement of the cup and to close the passage upon forward movement of the cup.

Signed at Boston, Massachusetts, this 26th 80 day of September, 1921.

OLIVER MITCHELL.
